UNITED STATES PATENT OFFICE

1,929,093

ASH QUENCHER

John J. Fry, Roxborough, Pa., assignor to The Allen-Sherman-Hoff Company, a corporation of Pennsylvania

Application April 10, 1930. Serial No. 443,066

9 Claims. (Cl. 110—171)

This invention relates to the art of ash hoppers and furnace bottoms of fuel burning furnaces and more particularly to the construction of certain parts of such devices.

5 It is common practice in powdered-fuel-burning furnace construction to provide a combustion chamber, with a refractory lining, the bottom wall having a discharge opening for the escape of slag, ashes and other incombustible

10 residues and ordinarily referred to as a furnace bottom. It is also common practice in stoker fired furnaces to provide an ash hopper having upstanding sides, refractory lined, for receiving ashes from the furnace. The temperature of

15 the ash and slag passing through the bottom opening of the furnace is very high, portions of the material frequently being in a molten state.

It is desirable to cool the ash and slag which pass through the furnace bottom, at least to a certain degree, before allowing it to enter the conveying mechanism which carries it to a place of disposal. In stoker fired furnaces, metallic lining has been provided immediately adjacent the opening in the bottom of the furnace. Such

20 linings serve to assist in the support of the refractory brick or the like, which line the furnace bottom and also provide a wear-resisting rim or nose portion for the discharge opening of the furnace. A lining of this general type is disclosed in the co-pending application of Sherman and Hoff, Serial No. 90,471, filed February 25, 1926.

It is also common practice in both powdered fuel and stoker fired furnaces to spray the hot slag and ash with water after they pass through the discharge opening in the furnace bottom. Spray nozzles have been provided in the upstanding ash hopper walls, the individual nozzles being set in the refractory lining of the walls.

25 In the herein described construction I have combined the metal lining for the discharge opening of the furnace bottom and a spray nozzle in an integral structure. This simplifies the furnace construction and provides an efficient and economical ash cooling means and furnace discharge opening lining.

One object of my invention is to provide a sectional water-cooled lining for bottom openings of furnaces and the like, having integral spray nozzles, in which the water which cools the casting is sprayed out through the nozzles and serves to cool the combustion residues passing through the discharge opening in the furnace bottom.

30 A further object of my invention is the provision of a nose or margin casting for furnace bot-

toms which will serve to cool the molten material which passes over it and further cool the material by spraying water directly into it as it drops into the ash hopper.

Other objects of my invention will appear from the following description of a preferred form thereof, reference being had to the accompanying drawings in which:

Fig. 1 is a vertical section through a furnace bottom showing my improved nose construction; 65

Fig. 2 is a fragmentary plan view taken on line 2—2 of Fig. 1 showing one of the metal block units together with its cooling-water connections; the adjacent supporting structure being omitted;

Fig. 3 is a section taken on line 3—3 of Fig. 2; 70

Fig. 4 is an enlarged sectional view taken on line 4—4 of Fig. 2;

Fig. 5 is a section taken on line 5—5 of Fig. 4.

The furnace bottom illustrated in Fig. 1 of the drawings has inwardly converging walls lined with a refractory material such as the fire brick 1. These walls are supported by a suitable external supporting structure and the lower row of firebrick rest on, and are supported by, the metallic angle members 2. 80

My improved cast nose or margin blocks are located immediately below the bottom row of firebrick. In the application of my invention illustrated in the drawings the blocks define the mouth of the bottom opening of the furnace. 85

The space between the bottom row of firebrick and the upper wall of the cooling chambers of the nose blocks 3 is preferably filled with a high temperature resisting cement 4 so that there will be a continuous and smooth surface for the products of combustion to pass over as they are discharged from the furnace. 90

The margin castings 3 are held in position on the supporting structure by the bolts 5. Immediately below the bottom opening of the furnace is an ash hopper 6, which may be of any desired and suitable form. The hopper illustrated in the drawings has vertical side walls which are lined with refractory material to provide a heat resisting and renewable surface. 95

The inner walls 7 of my nose castings, over which the hot products of combustion pass, are preferably curved as shown to facilitate the discharge of the material. These inner walls 7 form one side of the longitudinally extending water chambers 8 of the nose castings. 105

As seen in Figs. 1 and 2, the metallic rim or nose of the furnace bottom opening is preferably made in blocks or sections which are adapted to be assembled to define the opening in the bottom. 110

of the furnace. Each block is an independent unit and as they are substantially alike, a description of one will suffice.

The base 9 of each block extends rearwardly from the cooling-fluid chamber 8 and is provided with holes adjacent its rear edge, for the bolts 5. The fins 10 are spaced longitudinally on the base 9 of the unit and project upwardly therefrom. The upper edges of the fins 10 are adapted to contact with the angle irons 2 and they assist in supporting the converging walls of the furnace bottom, as well as strengthening the nose units.

As best seen in Fig. 4, the curved wall 7 overhangs the oblique wall 11 of the water chamber, forming lip or nose 12 which protects the spray nozzle 16 from the direct abrasive action of the material which is being discharged through the opening.

20 The water chamber 8 is connected by pipes 13 to the main water supply pipe 14. These pipes 13 enter the water chamber 8 through suitable openings in the rear verticle wall 15 of the chamber 8.

25 In the type of apparatus illustrated in the drawings a single spray nozzle is provided in each unit of the furnace nose. Any desired number of spray nozzles may, however, be provided in each unit.

30 In order to procure a whirling spray of water from the spray nozzle 16 and to maintain the proper water level in chamber 8, the auxiliary chamber 17 is provided within the main water chamber 8. This chamber 17 is connected to the chamber 8 by a pipe member 18 which has a passageway opening into the main water chamber 8 adjacent its top wall and entering the auxiliary chamber 17 at one side.

35 By having the opening of the pipe member 18 near the top of the water chamber 8, the level of the water in the chamber 8 will always remain high enough to prevent overheating of the casting and consequent burning of the metal. By locating this pipe member 18 on one side of the chamber 17, the water which enters this chamber will be given a whirling movement and will pass out of the nozzle 16 in the desired whirling spray form. A clean-out hole for the chamber 17 is normally closed by a plug 19, best seen in Fig. 4. If dirt or sediment collect in the chamber 17, it is only necessary to remove the plug 19, providing easy access to the chamber 17 from the outside of the furnace. The construction of the spray chamber 17 and the inlet pipe member 18 is similar to that disclosed in U. S. Patent No. 1,496,402 to F. B. Allen.

40 When my improved nose castings are in position to form the mouth of the opening in the bottom of the furnace and are connected to a supply of cooling water, this cooling water enters the chamber 8 through the pipes 13. The water rises in the chamber 8 until it is above the top of the opening in the pipe member 18. It then flows through this pipe member 18 into the chamber 17 where it is given a whirling movement and is discharged through the small hole 20 in the nozzle 16. The pressure of the water and the size of the pipes 13 will be made sufficiently large, in proportion to the size of the openings 20 in the nozzles 16, to cause the chambers 8 to be always filled with cooling water.

45 Thus it will be seen that the cooling water enters the chambers 8, serves to cool the hollow blocks and particularly their inner walls 7, and then passes out through the spray nozzles 16 which

direct the water into the hot ash and slag as they pass through the opening in the furnace bottom. The water cooling of the castings positively prevents them from being burned out and also serves to cool the molten slag which runs over their surfaces. The sprays of water issuing from the nozzle 16 are directed out into the path of the falling combustion residues and serve to thoroughly cool them before they enter into the conveyor or other removing means.

50 The water-cooled metal blocks 3 form in effect a part of the lining of the furnace bottom. They are not necessarily located at the mouth of the discharge opening but may be inserted in the refractory lining at any desired and suitable point.

55 While I have described the illustrated embodiment of my invention in some detail, modifications and variations thereof may occur to those skilled in the art to which this appertains and I do not therefore, limit myself to the precise details shown and described but claim as my invention all embodiments thereof coming within the scope of the appended claims.

I claim:

1. A furnace bottom having an ash discharge opening, an ash hopper below said opening, a metallic margin member defining said opening, said margin member having a cooling-water chamber and an auxiliary water chamber within said cooling water chamber, a conduit within said margin member extending from a point above the bottom of said cooling water chamber into said auxiliary water chamber, a spray nozzle in the wall of said auxiliary chamber having an aperture positioned to direct a spray of water from said auxiliary chamber into said ash hopper, and means for connecting a source of supply of water to said cooling water chamber.

2. A furnace bottom having a discharge opening, an ash hopper below said opening, a plurality of metal blocks having cooling-water chambers disposed around said opening, means for connecting a source of supply of cooling-water to said cooling chambers, auxiliary water chambers within said cooling-water chambers, means permitting water to enter said auxiliary chamber from said cooling-water chamber and for producing a whirling motion of the water within said auxiliary chamber, said auxiliary chamber having a normally closed cleanout opening, and a spray nozzle opening out of said auxiliary chamber.

3. A refractory lined furnace bottom having a discharge opening, a plurality of metal blocks positioned to form a part of the lining of the furnace bottom and having cooling water chambers, auxiliary water chambers within said cooling-water chambers, fluid conducting conduits connecting the cooling water chambers and the auxiliary water chambers, and spray nozzles in the walls of said blocks adapted to spray water from said auxiliary chambers.

4. A furnace bottom having a discharge opening, a plurality of metal margin units having cooling water chambers disposed around said opening, means for connecting a source of supply of cooling water to said cooling-water chambers, auxiliary water chambers within said cooling water chambers, fluid conducting passages between said auxiliary chambers and said cooling-water chambers, and spray nozzles in the walls of said auxiliary chamber positioned to spray water from said auxiliary chambers into the path of material passing through said discharge opening.

5. In a furnace having an ash discharge open-

- ing, a lining for the mouth of said opening comprising a casting having a cooling-water chamber, an auxiliary water chamber lying within said cooling-water chamber, a pipe leading from said cooling-water chamber to said auxiliary chamber, and a spray nozzle having an aperture through which water may be discharged from said auxiliary chamber into the path of material passing through said furnace bottom opening. 80
- 10 6. A hollow margin block for furnace bottom openings, including walls defining a cooling water chamber, walls defining an auxiliary chamber within said cooling water chamber and a pipe connecting said chambers, said pipe having its opening into said cooling water chamber disposed above the bottom thereof. 85
- 15 7. A margin block of the class described including walls defining a main cooling water chamber and an auxiliary water chamber, said auxiliary chamber having a water discharge outlet, and a fluid conducting conduit extending between said main and auxiliary chamber, said conduit having its opening into said main chamber disposed above the bottom thereof. 90
- 20 8. A furnace bottom having a discharge opening, an ash hopper below said opening, a plurality 95
- 25 of hollow water cooled metal blocks disposed around said opening, means outside of said furnace bottom and ash hopper for connecting a source of supply of cooling water to said metal blocks, each of said blocks having a cooling water chamber and an auxiliary water chamber within said cooling water chamber, conduits within said hollow blocks extending from a point above the bottoms of said cooling water chambers into said auxiliary chambers and spray nozzles in the wall of said auxiliary chambers positioned to spray water therefrom into said ash hopper. 100
9. In combination with a furnace bottom having a discharge opening and an ash hopper below said opening, a metal margin block for said opening having a cooling water chamber, means for connecting a source of supply of cooling water to said cooling water chamber, an auxiliary chamber within said cooling water chamber, means permitting water to enter said auxiliary chamber from said cooling water chamber and for producing a whirling motion of the water within said auxiliary chamber, and a spray nozzle opening out of said auxiliary chamber. 105
